CLAIM

The ornamental design for a sliding door track as shown and described.

DESCRIPTION

FIG. 1 is a perspective view of the sliding door track of the present invention;

FIG. 2 is a front view thereof;

FIG. 3 is a rear view thereof;

FIG. 4 is a left side view thereof;

FIG. 5 is a right side view thereof;

FIG. 6 is top view thereof;

FIG. 7 is a bottom view thereof; and,

FIG. 8 is bottom perspective view thereof.

The broken lines shown in the drawings illustrate portions of the article that form no part of the claimed design. The article is shown with a symbolic break in its length, delineated by dot-dash broken lines. The appearance of the break lines, and any portion of the article between the break lines, forms no part of the claimed design.

1 Claim, 7 Drawing Sheets
